[57] CLAIM

The ornamental design for a plunger rod/needle protector for a hypodermic syringe, as shown and described.

DESCRIPTION

FIG. 1 is a side elevation of a plunger rod/needle protector for a hypodermic syringe showing our new design,

FIG. 2 is an end view taken from the right of FIG. 1,

FIG. 3 is a perspective view thereof; and

FIG. 4 is a perspective view in the opposite direction of

that of FIG. 3.
